UNITED STATES PATENT OFFICE.

WILLIAM B. FOSTER, OF UTICA, NEW YORK, ASSIGNOR TO FOSTER BROTHERS MANUFACTURING COMPANY, OF UTICA, NEW YORK, A CORPORATION.

CUSHION FOR SLIDING-SIDE CRIBS.

1,345,485.

Specification of Letters Patent.

Patented July 6, 1920.

Application filed April 16, 1919. Serial No. 290,519.

To all whom it may concern:

Be it known that I, WILLIAM B. FOSTER, a citizen of the United States, and a resident of the city of Utica, in the county of Oneida and State of New York, have invented certain new and useful Improvements in Cushions for Sliding-Side Cribs; and I do hereby declare that the following is a full, clear, and exact description thereof, which will enable others skilled in the art to which it appertains to make and use the same, reference being had to the accompanying drawings, and to the reference-numerals marked thereon, which form part of this specification.

15 My present invention relates to cushioned joints for sliding side cribs.

The purpose of my invention is to provide an improved cushioned joint whereby the descent of the sliding side of a crib is cushioned at the end of its travel to prevent jar, vibration and noise. A further object of my invention is to provide a device of the character described which is simple in 20 construction and operation, readily applied to the crib either when first made or when replaced and which will be highly efficient in operation.

Another aim of this invention is to provide an article of the class described which will not interfere with the usual or ready operation of the sliding side and at the same time will be automatic in operation, that is the cushion will positively re-position itself when the weight of the side is removed from the cushion so that the cushion is ready without attention from the operator for the next movement of the sliding side. Further purposes and advantages of my 25 invention will appear from the specification and claims herein.

Figure 1 is a side elevation of the corner of a sliding side crib equipped with an embodiment of my invention, the parts being 30 shown in the position they occupy when the side has engaged the cushion but before the cushion has yielded under the weight thereof.

Fig. 2 is a view partly in side elevation and partly in vertical section of the cushion and adjacent parts in the same position.

Fig. 3 is a view similar to Fig. 2 but with the cushion compressed.

Fig. 4 is a top or bottom view of the 45 cushion.

Fig. 5 is a horizontal central section through the said cushion.

Referring to drawings in a more particular description it will be seen there is shown the corner post 6 of a crib having mounted 50 thereon but spaced therefrom a guide rod 7 as by the lower end of said guide rod being secured to a bracket 8 which in turn is secured to the lower part of the corner post 6 while the upper end of the guide rod is 55 secured to the upper part of the corner post as by having the upper end 9 of said guide rod 7 bent toward and extended to the adjacent part of said corner post and secured thereto by suitable means as by a screw 10. 60

The sliding side designated in general by the numeral 11 is composed of suitable vertical filling bars 12 and horizontal rods 13 at the top and bottom of said sides. The ends of these horizontal rods 13 are provided with eyes 14 through which extend 65 the guide rods 7 of the crib whereby in obvious manner the side 11 is slidingly mounted upon the crib.

Mounted upon each guide rod 7 immediately above the bracket 8 is a hollow air-filled, collapsible and resilient member 15 preferably spherical in general outline and conveniently and preferably formed of a hollow rubber ball. This 70 cushion member or rubber ball 15 is provided with upper and lower apertures 16 of a shape and size slidingly fitting the guide rod 7 which extends through the cushion member. At its aperture 16 the 75 ball fits the guide rod 7 loosely enough to slide fairly readily thereon but tight enough to have the air confined within the ball escape only gradually when the ball is compressed through the dropping of the sliding 80 side. Due to this sliding fit of the rubber ball upon the guide rod 7 and also to the collapsible character of the material and construction of the cushion member 15, said 85 member will be compressed when the dropping of the side brings the lower horizontal rod 13 into contact with the upper part of the cushion member. Under the sharp impact from the sliding side the cushion member will first yield to a considerable extent 90 through the yielding character of its side walls and through the air confined therein, being compressed by the compression of said cushion member. The construction of the 95 cushion and the fit thereof upon the guide 100

105

110

rod 7 is such that the air compressed within the cushion will not escape at once but will take an appreciable time to escape after the weight of the side is received. In other words, the descent of the side will be cushioned first by the ball 15 partly collapsing and placing the air therein under pressure and then more gradually and slowly collapsing as the air compressed therein escapes. This will result in a very slow final collapse of the cushion. In this way all jar, vibration and noise is entirely prevented or overcome and the sliding side even though dropped from the top of its travel to the bottom will be properly cushioned and will make no noise or unpleasant vibration.

The construction of the cushioned member 15 and its fit upon the rod 7 is such that if the weight of the sliding side is removed from the collapsed cushion, said cushion will of its own accord expand again to its natural or spherical shape due to the resiliency of the cushion and its tendency to resume its normal shape. This tendency to resume its normal shape will be strong enough to slide the upper part of the ball upon the guide rod 7 during which process the ball will again become filled with air. The device it will then be seen is ready for the next downward movement of the sliding side.

In order to get a greater bearing surface on the top and bottom of the cushion member 15 and in order to get a better sliding fit of the desired tightness upon the guide rod 7, the top and bottom of said member will be provided with axially extending flanges 17 spaced a little from the guide rod 7 and at the end thereof with a diaphragm 18 extending in to the guide rod. In these diaphragms 18 are provided the apertures 16.

It will now be seen that I have produced a cushion joint for sliding side cribs having the advantages and well fulfilling the purposes set forth at the beginning of this specification.

It will be noted particularly that the cushion members 15 may be readily mounted upon the guide rod 7 when the crib is being assembled by the merchant or user and that the said cushion members may be readily removed and replaced as occasion requires. It is found, however, from use and experimenting that a set of rubber balls 55 will last a good many months before they become too distorted or worn to be effectual.

What I claim as new and desire to secure by Letters Patent is:

1. A cushioning device adapted to be interposed between approaching members, consisting of a hollow, air-filled, collapsible and resilient member having two oppositely disposed openings and a guide rod extending through said openings and holding said collapsible member in position but allowing contraction and expansion thereof lengthwise of said rod, said hollow member fitting said guide rod so as to allow the gradual escape of air therefrom as the member is compressed and to allow the gradual inflow of air thereto when the weight is removed and the cushion expands.

2. The combination in a crib of a sliding side having horizontal bars, vertical guide rods at each end of the crib on which the horizontal bars of the side are slidingly mounted, hollow, air-filled, collapsible and resilient rubber balls having perforations at 80 their tops and bottoms whereby the balls are mounted on said guide rods at the bottom of the travel of one of the horizontal bars of the side and will cushion the descent of the side by yielding through compression 85 of the air within the balls and through the gradual escape of the air therefrom about the guide rod, said balls being adapted to resume their expanded shape and become filled with air upon removal of the weight 90 of the side.

In witness whereof I have affixed my signature, this 3rd day of March, 1919.

WILLIAM B. FOSTER.
